UNITED STATES PATENT OFFICE

ALBERT BOUWERS, OF EINDHOVEN, NETHERLANDS, ASSIGNOR TO N. V. PHILIPS' GLOEILAMPENFABRIEKEN, OF EINDHOVEN, NETHERLANDS

PORTABLE HIGH TENSION TRANSFORMER

Original application filed July 13, 1928, Serial No. 292,390, and in the Netherlands August 5, 1927. Divided and this application filed December 15, 1930. Serial No. 502,523.

This invention relates to an electric apparatus comprising a portable transformer for high tension and forms a division of my application Ser. No. 292,390 filed July 13th, 5 1928.

Such an apparatus may for example be an X-ray installation in which a discharge tube for radiating X-rays is connected by means of flexible cables with a supply transformer.

10 In order to make the conveyance of the apparatus easier the cables may be detachable and a handle may be provided by means of which the transformer is carried.

An object of the invention is to simplify 15 the construction of such a transformer.

Another object is a construction preventing that undesired articles penetrate into apertures of the envelope of the transformer during the conveyance.

20 A further object is to reduce the volume of such a transformer and to facilitate the fastening of the cables to the envelope.

Other objects will appear from the following description, in which reference is had to 25 the accompanying drawing.

In this drawing Fig. 1 is a perspective side view of the transformer provided with a handle for conveyance and

Fig. 2 is a section of an X-ray apparatus 30 comprising a high tension transformer to which cables are connected.

Referring to Figure 2 the X-ray tube is designated by 1, high tension cables with a metal outer sheath by 2 and 3, the transformer by 35 4. The X-ray tube has a wall comprising a glass part 5 and a metal part 6. The cathode of the tube is denoted by 13 and is surrounded by a focusing device 8. The X-rays emitted by the anticathode 7 leave the tube through 40 window 9. The anticathode has connected to it a cooling rod 10 which also serves as a current conductor. The cathode 13 has lead-ing-in wires 11 and 12 sealed in the pinch 14 forming part of the stem 15. One of these 45 wires comprises a resistance 46. The glass parts of the tube are surrounded by insulating cylinders 18 which together with the tube are enclosed in a metal envelope 16.

An enclosing envelope 20 surrounds the 50 transformer 4. The high tension winding of

the transformer terminates at one side in bipolar contact members 33 and 34 between which a tension prevails sufficient for heating the incandescent cathode 13 of the tube and which are connected to the cathode by means 55 of cable 3. At the other side the transformer winding terminates in contact member 36 designed to be connected with the anticathode 10 of the tube by means of cable 2.

The contact members 36, 33 and 34 are embedded in a block 19 of insulating material arranged in the envelope 20 and are located behind apertures in the cover of this envelope through which terminal pieces 22 and 24 of the cables 3 and 2 extend. The terminal 60 piece 22 bears bipolar contact members 31 and 32 which engage the members 33 and 34. Thus the terminal piece 24 bears a bar shaped contact member 35 which is embraced by contact member 36. 65

In the same way the cables are connected to the poles of the tube by means of terminal pieces 21 and 23.

The terminal pieces 22 and 24 engage tightly the block 19 which has cylindrical humps 70 75 37 embracing members 22 and 24.

The apertures which permit the insertion of the cable ends into the housing 20 are surrounded by threaded nipples on which are screwed gland nuts 48. By these means the 80 terminal pieces 22 and 24 are forced against the block 19 and the cables are rigidly fixed to the housing 20.

The other ends of the cables are likewise secured to the envelope 16 of the tube. When 85 the apparatus is not in use the cables are removed and the apertures in the housing 20 shut off. For this purpose a special cover is provided consisting of a bracket 51. This bracket is constructed as a handle and on its 90 ends gland nuts 53 are arranged which are screwed on the threaded nipples in the same way as the nuts 48.

After having disconnected the apparatus by unscrewing the nuts 48 and removing the 95 cables, the operator places the carrying handle with its ends on the apertures in the cover of the housing and screws up nuts 53. The transformer is then ready for conveyance. At the same time the apertures are shut off 100

and the danger that undesired articles get into the envelope of the transformer is avoided.

For the purpose of grounding the apparatus during the operation the housing 20 of the transformer has a terminal 50.

What I claim is:

1. A transformer, comprising an enclosing envelope, a high tension transformer winding mounted therein, contact members disposed in said envelope and located behind apertures in the wall thereof, and in which contact members the high tension winding of the transformer terminates the said contact members being adapted to interchangeably and lockingly receive a handle and high tension cables, the said handle, when in position, closing the said apertures.

2. A transformer, comprising an enclosing envelope, transformer windings mounted in said envelope, contact members in which the high tension winding of said transformer terminates, the said contact members being disposed within said envelope and behind apertures in the wall thereof, the said contact members being adapted to interchangeably and lockingly receive high tension cables and a substantially U-shaped handle.

3. A high tension transformer, comprising an enclosing envelope, transformer windings disposed in said envelope, and contact members disposed within said envelope and in which the high tension winding of the transformer terminates, the said contacts having threaded nipples adapted to interchangeably and lockingly retain high tension cables and a conveying handle.

4. A transformer, comprising an enclosing envelope having perforations therein, transformer windings in said envelope, contact members disposed beneath the perforations of the enclosing envelope and in which the secondary winding of said transformer terminates, a plate disposed in said envelope for supporting said contact members and providing recesses adapted for the reception of high tension cables, and threaded nipples provided on said envelope, above said plate, for interchangeably and lockingly receiving said cables and a handle.

5. A transformer adapted for interchangeably and lockingly receiving a conveying handle and high tension cables, comprising an enclosing envelope having perforations therein, transformer windings disposed in said envelope, contact members disposed in said envelope beneath said perforations and receiving the ends of the high tension windings of said transformer, insulating terminal pieces at the ends of the cables and fitting in said perforations, contact elements on the said terminal pieces adapted for electrical connection with the contact members within the envelope, and gland nuts on both the cables and the handle whereby the latter may

be interchangeably and lockingly disposed over said perforations.

In testimony whereof I have signed my name to this specification.
